J. R. Wheeler.
Thrashing Mach.
Patented Apr. 9, 1833.

Position of the Cylinders

April 9, 1833

No. 1833

411

John R. Wheeler of Brighton, Monroe Co., New York,
Letter Patent,

The Schedule referred to in this Letter Patent and making part
of the same, containing a description in the words of the said John
R. Wheeler himself of his improvement in the Threshing Machine,

To all to whom these presents shall come, Be it known, that I
John R. Wheeler of Brighton in the County of Monroe and State of
New York have invented a new and useful improvement not
known or used before my application, known by the name and
style of Wheeler's intersecting cylindrical machine for threshing
Wheat and other seeds, hulling Barley Rice &c. The following
is a full and exact description of the construction and operation
of the machine as invented by me.

A frame two and one half feet square & three
feet high, with posts at the corners, and rails near the top also
within one foot of the bottom. In this frame stand the cylinders,
perpendicular, and mesh or run into each other, by con-
centrated circular grooves, and feather edged circular ribs.
Each cylinder is composed of a number of sectional parts and
informed thus. A plate or ring of cast iron ten inches diameter
with an eye or hollow centre from one third to one fifth of its
diameter with a flange or rim to extend the eye to graduate the
space when on the shaft. At the eye this plate or ring is three
fourths of an inch thick terminating in a feather edge at the
circumference. The lines which form this section, make an acute
angled triangle, or an isosceles triangle, the two sides forming
the acute angle, continued round the cylindrical shaft until
they meet, are two end like inclined circular planes, together with
the plane subtending the acute angle, which forms the eye and on
one side extended, give the section required. And on these inclined
planes ribs or ridges are found, making furrows and gutters, like
the coffee mill grinder, or the mill stone in a concentrated or octagon

1520 X

regular triangular bridges and grooves. Each cylinder is composed of all
members of the above sections, and when closely connected in the right
order parallel among themselves forming equal channels & ridges. These
cylinders may be increased to any size or length that fancy may dictate,
the one adopted is from 1 foot to fifteen inches long, the small
est for practical use. Two of these cylinders are placed to run
at right angles to each other and so close as not to interfere. The third must intersect
its bevelled edge & rib, with the channels of both the others equal,
leaving room only between the bevelled groove and rib for the
grain to pass without breaking it. These cylinders when in opera-
tion should severally move without interfering one with another
when geared by cog and spur wheel, to graduate them several mo-
ments, so that when the power is applied either by water, steam, horse,
or otherwise to one of the receiving cylinders, the other will move
at the same time. The third which receives the straw after it passes
the others, moves astern to one with the second.

All the above I claim together with the privi-
lege of varying the proportion of the said machine in construction
or making the cylinders of wrought or cast iron, or changing them
from a perpendicular to a horizontal position as my fancy may
dictate provided always I keep within the principles of my
invention. In testimony whereof I the said John A. Wheeler
have hereunto set my hand and seal this twenty-fifth day of
March one thousand eight hundred and thirty three.
